RAILWAY TRAFFIC CONTROLLING APPARATUS

Original Filed Aug. 11, 1926

UNITED STATES PATENT OFFICE

HERBERT A. WALLACE, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed August 11, 1926, Serial No. 128,597. Renewed July 3, 1930.

My invention relates to railway traffic controlling apparatus, and particularly to apparatus of the type comprising train carried governing means controlled by energy received from the trackway. More particularly my present invention relates to the train carried portion of such apparatus.

One object of the present invention is the provision, in apparatus of the type described, of means operating in conjunction with the usual automatic brake applying mechanism to cause an automatic application of the brakes after the expiration of a time interval following a change in traffic conditions. Acknowledging means are also provided under the control of the engineman and effective if operated during such time interval to prevent an automatic brake application.

I will describe one form of railway traffic controlling apparatus embodying my invention, and will then point out the novel features thereof in claims.

The accompanying drawing is a view, partially diagrammatic, illustrating one form of railway traffic controlling apparatus embodying my invention.

Referring to the drawing, the reference character R designates a train carried relay which is controlled by traffic conditions in advance of the train by means forming no part of my present disclosure and omitted from the drawing for the sake of simplicity. For present purposes it is sufficient to state that when traffic conditions in advance are safe relay R is energized, but that when traffic conditions in advance are unsafe, relay R is de-energized.

The train is also provided with a magnet valve, designated by the reference character A, and comprising a valve stem 1 provided with an armature 3 and a winding 2. The winding 2 is provided with a circuit controlled by relay R and by a manually operable circuit controller J having a normal contact 33-34 and a reverse contact 33-35. The circuit for winding 2 of magnet valve A may be traced from terminal a of a suitable source of energy (not shown in the drawing) through contact 33-34 of circuit controller J, wires 36 and 37, front contact 38 of relay

R, wires 52 and 39, winding 2 of valve A and back to terminal b of the same source. When this circuit is closed stem 1 of valve A is moved downwardly against the bias of a spring 4 so that pipe 6 is connected through pipe 5 with a source of fluid pressure not shown in the drawing. When winding 2 is de-energized, however, stem 1 rises to blank pipe 5 and connect pipe 6 with atmosphere through a restrictive orifice 8.

Pipe 6 is constantly connected with a timing reservoir 7 and with chamber 9 of a stop valve B. A flexible diaphragm 10 forms one wall of chamber 9 and controls a stem 11 which is normally urged into an upper, or normal, position by a spring 12. When valve A is energized so that reservoir 7 and pipe 6 are charged with fluid pressure, this pressure is supplied also to chamber 9 so that stem 11 is moved to its lower, or reverse, position in which pipe 13 is connected with atmosphere through port 14 and pipe 15 is blanked.

When the pressure in chamber 9 is sufficiently reduced however, as by leakage through orifice 8 when valve A is de-energized, stem 11 rises and disconnects pipe 13 from port 14 and connects pipe 13 with pipe 15. The parts are so proportioned that after de-energization of valve A a considerable interval of time elapses prior to the reversal of valve B.

The reference character G designates an application valve comprising two chambers 16 and 17 separated by a reciprocable piston 18 which is constantly urged to the left by a spring 19. The piston 18 also carries a slide valve 20. Chamber 16 is constantly supplied with fluid pressure from a source not shown in the drawing through pipe 5^a, and chamber 17 is constantly connected with pipe 15. The piston 18 is also provided with a restricted orifice 18^a so that when pipe 15 is blanked, pressure from chamber 16 flowing through orifice 18^a builds up in chamber 17. The combined forces of the pressure in chamber 17 and spring 19 moves piston 18 to the left-hand or normal position. When valve B is reversed, however, that is, when stem 11 rises, pipe 15 is connected through pipe 13 with a stop reservoir 53. This reservoir is nor-

mally connected with atmosphere through port 14 of valve B so that when valve B reverses, establishing the connection just described the pressure in chamber 17 is reduced. 5 Piston 18 of valve G therefore moves to its right-hand or reverse position. This movement of the piston connects pipe 13, and hence reservoir 53, directly with atmosphere through a restricted orifice 21, but reservoir 10 53 is connected with pipe 15 so that this operation of the valve 20 connects chamber 17 of valve G with atmosphere through orifice 21. At the same time a branch 15^a of pipe 15 is connected with atmosphere through pipe 15, valve 24 and port 23 of the usual engineerman's brake valve C. The valve 24 is closed 15 only when the engineman's brake valve is in the lap position.

The application valve G is arranged to 20 cause an automatic application of the brakes when this valve is reversed. The control of the automatic brake applying mechanism by the valve G forms no part of my present invention and is omitted from the drawing for 25 the sake of simplicity.

The reference character H designates a 30 pneumatic relay comprising a chamber 25 connected with pipe 15 and containing a flexible diaphragm 26. A plunger 27 is urged downwardly by a spring 28 but when pipe 15 is charged with fluid pressure diaphragm 26 moves plunger 27 upwardly so that contact 29 is closed. When the pressure in pipe 15 is reduced, however, spring 28 moves plunger 35 27 downwardly and opens contact 29. The pneumatic relay H together with the circuit controller J control an acknowledging relay D. This relay is normally de-energized but if circuit controller J is reversed when contact 40 29 of relay H is closed a pick-up circuit is completed for relay D over which current flows from terminal a, through reverse contact 33—35 of circuit controller J, wire 40, contact 29 of relay H, wires 41 and 42, winding of relay D, and back to terminal b. The 45 relay D therefore becomes energized, and if relay R is de-energized a stick circuit is completed for the relay D which may be traced from terminal a, through back contact 30—30^b of relay R, wires 43 and 44, front contact 45 of relay D, wires 46 and 42, winding of relay D and back to terminal b. It 50 will therefore be seen that if circuit controller J is operated when contact 29 of relay H is closed and when relay R is de-energized, relay D will be picked up and will be maintained in its energized condition as long as relay R is de-energized even though circuit controller J is returned to its normal position. 55 When relay D is energized and circuit controller J operated to close its normal contact an auxiliary circuit for magnet valve A is closed from terminal a, through normal contact 33—34 of circuit controller J, wires 36 and 47, front contact 48 of relay D, wires 49

and 39, winding 2 of magnet valve A and back to terminal b. It will therefore be plain that if relay D is energized, and circuit controller J occupies its normal position, the front contact 38 of relay R is removed from the control of the magnet valve A. 70

In explaining the operation of the apparatus as a whole, I will assume that relay R is energized as shown in the drawing and that circuit controller J occupies its normal position so that magnet valve A is energized over front contact 38 of relay R. Under these conditions contact 30—30^a of relay R is also closed and current is supplied to a lamp 31, lighting this lamp to give a proceed indication. Stem 1 of valve A occupies its lower position so that reservoir 7 and pipe 6 are charged with fluid pressure and stem 11 of valve B occupies its normal position. Pipe 15 is charged with fluid pressure from chamber 17, this pipe being blanked at valve B, and also at valve 20 because the application valve G is in its normal position. The brakes are therefore released and relay H is supplied with fluid pressures so that contact 29 is closed. Relay D is de-energized, its stick circuit being open at back contact 30—30^b of relay R and its pickup circuit being open at circuit controller J. 85

I will now assume that relay R becomes de- 95 energized as by a change from safe to unsafe traffic conditions. The opening of front contact 30—30^a extinguishes lamp 31 and the closing of back contact 30—30^b completes a circuit for a second lamp 32 thereby lighting 100 this lamp to indicate stop. The opening of front contact 38 of relay R also interrupts the circuit for winding 2 of magnet valve A so that the valve reverses, connecting pipe 6 and reservoir 7 with atmosphere through port 8. Pressure in the reservoir 7 is slowly vented to atmosphere through port 8 and after the 105 expiration of a time interval valve B reverses to connect pipe 15 with reservoir 53 which had previously been connected with atmosphere through port 14. The pressure in pipe 15 is therefore reduced, and the pressure in chamber 17 is also reduced, thereby permitting pressure in chamber 16 to reverse valve G and apply the brakes. When this happens pipe 15^a is connected with atmosphere 110 through port 23 of the engineman's brake valve C and pipe 13 is connected with atmosphere through port 21 of valve G. 115

An automatic application of the brakes 120 can be prevented by the engineman if he acknowledges the change in traffic conditions by suitable operation of the circuit controller J. If circuit controller J is reversed during the time interval prior to the reversal of 125 valve B, the pick-up circuit for relay D is closed because contact 29 is still closed. The relay D is subsequently maintained in its energized condition over its own front contact 45 and back contact 30—30^b of relay R. If, 130

now, the engineman restores circuit controller J to its normal position the auxiliary circuit for winding 2 of magnet valve A is closed over front contact 48 of relay D. Stem 1 of valve A is moved downwardly and reservoir 7 and pipe 6 are again charged with fluid pressure. It will be seen therefore that if the engineman acknowledges the changes in traffic conditions by operation of circuit controller J before valve B reverses, he may prevent an automatic application of the brakes. If, however, valve B has once been reversed to cause reversal of valve G by decreasing the pressure in pipe 15, contact 29 of relay H opens so that the pick-up circuit for relay D can not be closed by operation of the circuit controller J.

It should further be noted that if the engineman attempts to acknowledge before relay R becomes de-energized the opening of normal contact 33-34 of circuit controller J opens the circuit for winding 2 of magnet valve A. This de-energization of the magnet valve commences the venting of reservoir 7 in exactly the same manner as if relay R had become de-energized. At the expiration of the time interval required for venting of reservoir 7, valve B will reverse and the consequent reversal of the valve G will cause an automatic application of the brakes. It, therefore, will be plain that if circuit controller J is operated too soon, that is, if this circuit controller is operated prior to the de-energization of relay R by a time interval greater than the interval required for reservoir 7 to vent, the brakes will be applied, because contact 29 of relay H will open and de-energize relay D, before back contact 30-30^b of relay R closes to complete the stick circuit for the relay D. It will also be plain that if the engineman waits after the de-energization of relay R for a time interval greater than that necessary to vent reservoir 7 the opening of contact 29 of relay H will prevent acknowledgment.

After the brakes have once been applied they may be released by restoring valve G to its original position. This can be accomplished only by proper manipulation of the release valve K which is preferably located at some position on the train in which it is accessible to the engineman only when the train is at rest. When valve K occupies its normal position in which it is illustrated in the drawing, pipe 15 is blanked and reservoir 50 is supplied with fluid pressure from a suitable source not shown in the drawing through pipe 5^b. When valve K is reversed, however, reservoir 50 is disconnected from pipe 5^b and is connected with pipe 15 and also with atmosphere through a restricted orifice 51. I will assume that the brakes have been applied by the reversal of valve G as has already been explained and that the engineman wishes to restore valve G to its original

position. To accomplish this, he moves his brake valve C to the lap position, thereby blanking pipe 22 and hence blanking pipe 15^a. He then operates circuit controller J so that contact 33-35 of this circuit controller is closed. Contact 29 of relay H is open, however, so that the pick-up circuit for relay D is also open. In order to close the pick-up circuit for relay D the engineman operates valve K. Pressure from reservoir 50 is then supplied to pipe 15 and chamber 17, and also to pipe 18 which is open to atmosphere at orifice 21, but the size of this orifice is such that sufficient pressure is created in chamber 17 to restore valve G to its normal position and in chamber 25 to close contact 29 of relay H. When the valve G has been returned to its normal position, pipe 15^a is blanked. The reverse contact 33-35 of circuit controller J has already been closed so that operation of relay H picks up relay D. Relay R is de-energized so that the stick circuit for relay D is closed and this relay remains in its energized condition as long as relay R is open. The engineman may then restore valve K to its normal condition, thereby blanking pipe 15 so that valve G remains in its normal position. The engineman then returns to his cab and restores circuit controller J to its normal condition thereby closing contact 33-34 and completing the auxiliary circuit for magnet valve A. The magnet valve is therefore restored to its normal condition, charging reservoir 7 and moving stem 11 of valve B to its lower position. Pipe 15 is therefore blanked at valve B and reservoir 50 is connected with atmosphere through port 14 to restore the apparatus to its normal condition.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. Railway traffic controlling apparatus comprising a train carried pipe normally charged with fluid pressure, mechanism responsive to a change in the pressure in the pipe to cause an automatic application of the brakes, a pneumatic relay responsive to the pressure in said pipe, means for causing a change in the pressure in said pipe upon the expiration of a time interval after a change in traffic conditions, and means controlled by said pneumatic relay for preventing an automatic application of the brakes.

2. Railway traffic controlling apparatus comprising a train carried pipe, normally charged with fluid pressure, mechanism responsive to a change in the pressure in the pipe to cause an automatic application of the

brakes, a pneumatic relay responsive to the pressure in said pipe, means for causing a change in the pressure in said pipe upon the expiration of a time interval after a 5 change in traffic conditions, and means controlled by said pneumatic relay for preventing operation of said mechanism.

3. Railway traffic controlling apparatus comprising a train carried pipe, normally charged with fluid pressure, mechanism responsive to a change in the pressure in the pipe to cause an automatic application of the brakes, a pneumatic relay responsive to the pressure in said pipe, means for causing a 10 change in the pressure in said pipe upon the expiration of a time interval after a change in traffic conditions, and manually controlled means controlled by said pneumatic relay for preventing operation of said mechanism.

15 4. Railway traffic controlling apparatus comprising a train carried pipe normally charged with fluid pressure, means for reducing the pressure in said pipe upon the expiration of a time interval after a change in traffic 20 conditions, mechanism responsive to a reduction of such pressure to cause an automatic application of the brakes, a normally closed contact arranged to open if the pressure in said pipe is reduced, and means controlled by 25 said contact for preventing an automatic application of the brakes.

5. Railway traffic controlling apparatus comprising a train carried pipe normally charged with fluid pressure, means for reducing the pressure in said pipe upon the expiration of a time interval after a change in traffic conditions, mechanism responsive to a reduction of such pressure to cause an automatic application of the brakes, a normally 30 closed contact arranged to open if the pressure in said pipe is reduced, and means controlled by the 35 relay for preventing an automatic application of the brakes.

40 6. Railway traffic controlling apparatus comprising a train carried pipe normally charged with fluid pressure, means for reducing the pressure in said pipe upon the expiration of a time interval after a change in traffic 45 conditions, mechanism responsive to a reduction of such pressure to cause an automatic application of the brakes, a normally closed contact arranged to open if the pressure in said pipe is reduced, a manually operable circuit controller, a relay controlled jointly by said contact and by said circuit controller, and means controlled by said relay 50 for preventing an automatic application of the 55 brakes.

60 7. Railway traffic controlling apparatus comprising a train carried magnet valve, mechanism for causing an automatic application of the brakes upon the expiration of an interval of time after de-energization of the 65 magnet valve, a normally closed contact ar-

ranged to open at the expiration of such time interval, a train carried relay arranged to be energized only when traffic conditions are safe, a manually operable circuit controller having a normal and a reverse contact, an acknowledging relay having a pick-up circuit including said normally closed contact and the reverse contact of said circuit controller, a stick circuit for said acknowledging relay including its own front contact and a back contact of said train carried relay, and a circuit for said magnet valve including a front contact of said train carried relay and a front contact of said acknowledging relay in parallel and the normal contact of said circuit controller.

70 8. Railway traffic controlling apparatus comprising a train carried magnet valve, mechanism for causing an automatic application of the brakes upon the expiration of an interval of time after de-energization of the magnet valve, a normally closed contact arranged to open at the expiration of such time interval, a train carried relay arranged to be energized only when traffic conditions are 75 safe, a circuit for said magnet valve including a front contact of said relay, and manually controlled means controlled by said normally closed contact for at times shunting said front contact of the relay.

80 9. Railway traffic controlling apparatus comprising a train carried magnet valve, means for energizing said magnet valve only under safe traffic conditions, mechanism for causing an automatic application of the brakes upon the expiration of a time interval after de-energization of said magnet valve, a normally closed contact arranged to open at the expiration of said time interval, manually operable means for reclosing said contact 85 for an interval of time and means controlled by said contact for energizing said magnet valve.

90 10. Railway traffic controlling apparatus comprising a train carried relay energized only under safe traffic conditions, a magnet valve, a circuit for said magnet valve including a front contact of the relay, mechanism for causing an automatic application of the brakes upon the expiration of a time interval after de-energization of said magnet valve, a normally closed contact arranged to open at the expiration of said time interval, manually operable means effective when operated to close said contact, and manually controlled means including said contact for energizing said magnet valve independently of said front contact of the relay.

95 11. Railway traffic controlling apparatus comprising a train carried pipe normally charged with fluid pressure, means for reducing the pressure in said pipe upon the expiration of a time interval after a change in traffic conditions, mechanism responsive to a reduction of such pressure to cause an auto- 100

matic application of the brakes, manually controlled means effective when operated to restore fluid pressure to said pipe, a normally closed contact arranged to open if the pressure in said pipe is reduced, and means controlled by said contact for preventing an automatic application of the brakes.

12. Railway traffic controlling apparatus comprising a train carried pipe normally charged with fluid pressure, mechanism responsive to a change in the pressure in such pipe to cause an automatic application of the brakes, a pneumatic relay responsive to the pressure in said pipe, means for causing a change in the pressure in said pipe upon the expiration of a time interval after a change in traffic conditions, manually operable means effective when operated to restore original fluid pressure to said pipe for a time interval, and means controlled by said pneumatic relay for permanently restoring original fluid pressure to said pipe.

13. Railway traffic controlling apparatus comprising a magnet valve, a pipe normally charged with fluid pressure, mechanism for causing an automatic application of the brakes when the pressure in the pipe is reduced, means for reducing the pressure in said pipe upon the expiration of a time interval after operation of the magnet valve, a pneumatic relay responsive to the pressure in said pipe, and a circuit for said magnet valve controlled by said pneumatic relay.

14. Railway traffic controlling apparatus comprising a magnet valve, a pipe normally charged with fluid pressure, mechanism for causing an automatic application of the brakes when the pressure in the pipe is reduced, means for reducing the pressure in said pipe upon the expiration of a time interval after operation of the magnet valve, a pneumatic relay responsive to the pressure in said pipe, a manually operable circuit controller, an acknowledging relay controlled by said pneumatic relay and by said circuit controller, and a circuit for said magnet valve controlled by said acknowledging relay.

15. Railway traffic controlling apparatus comprising a magnet valve, a pipe normally charged with fluid pressure, mechanism for causing an automatic application of the brakes when the pressure in the pipe is reduced, means for reducing the pressure in said pipe upon the expiration of a time interval after operation of the magnet valve, manually operable means effective when operated to restore original pressure in said pipe, a pneumatic relay responsive to the pressure in said pipe, and a circuit for said magnet valve controlled by said pneumatic relay.

16. Railway traffic controlling apparatus comprising a magnet valve, a pipe normally charged with fluid pressure, mechanism for

causing an automatic application of the brakes when the pressure in the pipe is reduced, means for reducing the pressure in said pipe upon the expiration of a time interval after operation of the magnet valve, a reservoir, an acknowledging valve for normally charging said reservoir with fluid pressure but effective when operated to connect the reservoir with said pipe and to simultaneously connect the reservoir with atmosphere through a restricted orifice, a pneumatic relay responsive to the pressure in said pipe, and a circuit for said magnet valve controlled by said pneumatic relay.

17. Railway traffic controlling apparatus comprising a train carried relay energized only under safe traffic conditions, a pipe normally charged with fluid pressure, mechanism for causing an automatic application of the brakes when the pressure in the pipe is reduced, a magnet valve, means effective upon the expiration of a time interval after deenergization of said magnet valve to reduce the pressure in said pipe, a reservoir, a manually operable valve for normally charging the reservoir with fluid pressure but effective when operated to connect the reservoir with said pipe and to simultaneously connect the reservoir with atmosphere through a restricted orifice, a pneumatic relay comprising a normally closed contact arranged to open if the pressure in said pipe is reduced, a manually operable circuit controller having a normal and a reverse contact, an acknowledging relay having a pickup circuit including the contact of the pneumatic relay and the reverse contact of the circuit controller, a stick circuit for said acknowledging relay including its own front contact and a back contact of said train carried relay, and a circuit for said magnet valve including a front contact of said train carried relay and a front contact of said acknowledging relay in parallel and the normal contact of said circuit controller.

In testimony whereof I affix my signature.
HERBERT A. WALLACE.
